J. O. THOMAS

COMBINATION SQUARE

Filed July 27, 1921

Lacy Lacy, Attorney

UNITED STATES PATENT OFFICE.

JOHN O. THOMAS, OF LONG BEACH, CALIFORNIA.

COMBINATION SQUARE.

Application filed July 27, 1921. Serial No. 488,010.

To all whom it may concern:

Be it known that I, JOHN O. THOMAS, a citizen of the United States, residing at Long Beach, in the county of Los Angeles and State of California, have invented certain new and useful Improvements in Combination Squares, of which the following is a specification.

The present invention relates to combination squares such as are generally used by carpenters, tool makers and machinists. My improvement in this kind of squares has now for its object to facilitate the laying out of squares and lengths and also for plotting bevels or angles of any size. This implement may also be advantageously used as an ordinary gage or butt gage.

One embodiment of the invention is illustrated in the accompanying drawing, in which—

Figure 1 shows a plan view of the combination square folded;

Figure 2 is a similar view with its adjusting leaf in working position;

Figure 3 is a top plan view of Figure 2.

A straight edge or blade 10 is securely fastened to the handle or beam 11 by means of rivets 12 to form a square. On the outer edge of the blade, suitable graduations 13 are provided. As will be seen in the figures, the outer edge of the blade 10 projects slightly beyond the end of the handle or beam 11 so that the reading of the graduation will not be interfered with.

The handle 11 may be made of two solid blocks spaced apart to form a narrow opening between them and the blade 10 riveted as at 12 to the end portion of the handle between said blocks. The handle 11 may also be made in two parts riveted together at the outer end of the handle at 14 with spacing blocks 15 inserted between them. A space is thus provided for the leaf 16 for sliding in and out, and an end opening 45 is provided between the spacing blocks 14 to hold the leaf 16 in housing position.

The straight edged leaf 16 is provided with a longitudinal slot 17 and it has a graduation 18 along both of its longest edges. At one end of the leaf 16 is provided a permanent gage point or scratching point 19 with which it is possible to mark the side lengths of the work piece.

A clamping bolt 20 is provided at the inner end of the handle 11 and this bolt engages in the longitudinal slot 17 of the

sliding leaf 16. For the purpose of tightening the leaf in any desired position, the clamping handle or wing nut 21 for the bolt 20 is provided on the upper side of the handle 11.

Figure 1 shows the implement folded as has been described and it is only necessary to loosen the wing nut 21 to swing the leaf 16 for the purpose of setting it at an angle, 65 as shown in full lines in Figure 2, for laying off a certain angle after the wing nut has again been tightened to hold the leaf rigidly in that position. As the leaf 16 may be turned completely around, it will 70 be readily understood that any angle may be laid off with this implement.

The sliding leaf 16 may also be used as an extension, as indicated in dotted lines in Figure 2, when it will form a straight edge 75 with the blade 10; as the position of the clamping screw with regard to the edge of the blade 10 is so selected that a longitudinal edge of the leaf 16 will coincide with the outer edge of the blade 10 when placed 80 parallel therewith.

Having thus described the invention, what is claimed as new is:

A measuring and plotting instrument comprising a beam consisting of two similar rectangular members arranged in parallelism one above the other, and spacing blocks between said members respectively at the corners of one end thereof, and means permanently securing said members and blocks together, said blocks being spaced to define an open passage between them, a straight-edged blade inserted between said members at the other end of the beam and rigidly attached to one of said members at 95 a right angle thereto while spaced from the other member, a straight-edged leaf disposed between said blade and the other member and having a longitudinal slot and adapted to be housed within the beam with one end extending through said passage or disposed in angular relation to the beam and the blade, a clamping screw passing through the beam and the blade at said other end and through the slot in the leaf, 105 and a nut on said screw adapted to be turned home against the other member of the beam to secure the leaf in a set position relative to the beam and the blade.

In testimony whereof I affix my signature.

JOHN O. THOMAS. [L. S.]
